P. H. GASKINS

CONVERTIBLE BODY FOR AUTOMOBILES

Filed Aug. 6, 1923

Fig. 1.

UNITED STATES PATENT OFFICE.

PALEMON H. GASKINS, OF JACKSONVILLE, FLORIDA.

CONVERTIBLE BODY FOR AUTOMOBILES.

Application filed August 6, 1923. Serial No. 655,970.

To all whom it may concern:

Be it known that I, PALEMON H. GASKINS, a citizen of the United States, and a resident of Jacksonville, in the county of Duval and State of Florida, have invented certain new and useful Improvements in Convertible Bodies for Automobiles, of which the following is a specification.

This invention relates to a convertible body for automobiles, and aims to provide a body of this character which can be readily and easily converted from an open to a closed type of body.

Another object is to provide a device of this character and having the foregoing advantages and capacities and wherein the glass panels and the other parts are firmly and rigidly supported when the car has been converted into a closed type of construction without liability of the parts breaking or being injured, and without the vibration ordinarily set up in the car being liable to produce chattering of the glass.

Another object is to provide a device of this character which is of simple and durable construction, reliable in operation, attractive in appearance, and easy and comparatively inexpensive to manufacture.

Other objects and advantages reside in certain novel features of the construction, arrangement and combination of parts which will be hereinafter fully described and particularly pointed out in the appended claims, reference being had to the accompanying drawings forming a part of this specification, and in which:

Figure 1 is a fragmentary perspective view showing a car body constructed in accordance with the present invention, with the parts shown in full lines as when positioned to provide an open type of car body, the position of the parts when providing a closed type of car body being indicated by dotted lines,

Figure 2 is a view partly in horizontal section and partly in top plan of a portion of one side of a car body and showing the parts of the present invention as positioned when providing a closed type of car body,

Figure 3 is a detail view of the swingable stanchion,

Figure 4 is a fragmentary perspective view illustrating the construction of the extensible stanchion, and

Figure 5 is a fragmentary detail view in section on the line 5—5 of Figure 1.

Referring to the drawings wherein for the sake of illustration is shown the preferred embodiment of the invention, the numeral 10 designates the car body which is supported on the frame in the conventional manner. On each side of the car body and intermediate the ends thereof, a post 11 upstands and is braced and supported by an angle iron 12 which frames the post and extends from one post to the other below the floor of the car. On each side of the car body, doors designated at 13 and 14 are provided, the door 13 being hinged to the car body as at 15, and the door 14 being hinged as at 16 to the post 11. As thus far described, the construction is such as is widely employed on certain types of cars.

The present invention is concerned with the means for mounting the glass panels designated at 17 and 18 on the doors 13 and 14 in such manner that they may be entirely concealed within the doors to provide an open type of car or in such manner that they may be disposed above the doors, and together with the doors, enclose the compartments of the car to provide a closed type of body construction. The means employed for so mounting the panels 17 and 18 are identical, so that a common description will apply to both.

The panels 17 and 18, when the car is to be converted into an open type, are disposed in the hollow doors 13 and 14 in accordance with the usual practice. Each of such glass panels is carried by a channel member 20 which is constructed of metal. Preferably, however, a strip of felt 21, (see Figure 2), is interposed between the channel member 20 and the glass engaged thereby. The channel 20 forms one part or member of an extensible stanchion, the other member of which is constituted by a second channel 22 into which the channel 20 telescopes or slidably fits. The sliding movement of the channel 20 relative to the channel 22 is limited by a pin 23 fixed to the channel 20 and operating in a longitudinal slot 24 provided in one of the flanges of the channel 22. The channel 22 is itself fitted for vertical sliding movement in the compartment of the door, and in order to constrain this channel member 22 to vertical sliding movement, one of its flanges is

provided with a guide rib 25 which is slidably fitted in a guide groove 26 provided in one of the walls of the door. The upper edge 27 of the flange 25 engages the top of the door to limit the upward movement of the channel member 22.

On the opposite side of the door from the extensible stanchion, a swingable stanchion 30 is pivotally mounted, as indicated at 31.

10 This swingable stanchion is also in the form of a channel as clearly shown in Figures 2 and 3, and its pivotal mounting on the door is such that it can swing from a horizontal position in which it fits in the upper open 15 end of the compartment of the door to a vertical position in which its longitudinal axis is aligned with the axis of swing of the door. When in its vertical position, the upper end of the channel 30 is releasably 20 secured in a resilient and yieldable socket 33 constructed of spring metal and having fingers 34 which fit around the upper end of the channel 30 to hold the same against lateral displacement while permitting rotary 25 or angular movement thereof. It is to be understood that the swingable stanchion 30 is of such length that it projects above the glass panel and it is the projecting portion of the stanchion that is engaged in the 30 socket 33.

When the car is to be converted from an open car to a closed car, the stanchion 30 is swung from its horizontal position to its vertical position, in which it is engaged in 35 the spring socket 33. Then when the glass panel is raised or slid upwardly, it slides in the channel 30. Upward movement of the panel is permitted by the action of the extensible stanchion made up of the channel 40 members 20 and 22, as the channel member 20 first slides relative to the channel member 22, and the channel member 22 next slides relatively to the door. It is to be understood that the usual hand crank operated means is 45 provided for raising and lowering the closed panel, this means usually comprising an element connected with the glass panel and operated by a pinion and other suitable gearing from the hand crank. When the glass 50 panels are in their upper position to close the car, they are firmly and rigidly supported by the extensible stanchion and by the swingable stanchion. The extensible stanchion has a firm and strong support or bearing in the door against lateral or longitudinal displacement, and the swingable stanchion is securely connected to the door and is firmly supported in the socket 33. As the 55 socket 33 is in vertical alignment with the hinges of the door the door may be readily opened and closed when the glass panels are elevated and the car has been converted into a closed type. Now when the panels have 60 been lowered and the swingable stanchions moved down onto the tops of the door, the

car is entirely open and no posts or obstructions interfere with the view or with the open features of the car.

It is to be understood that one of the sides of each door is removable to permit of the 70 assembly of the parts and also that the means conventionally employed for raising and lowering the panels or glass panes also hold them in adjusted position.

I claim:

1. A convertible automobile body having a door provided with a sliding glass panel, an extensible stanchion mounted on the door and connected with one side of the sliding glass panel, a swingable stanchion engaging 80 with the opposite side of the panel in the raised position thereof and foldable down over the top of the panel in the lower position thereof, and a socket aligned with the axis of swing of the door and adapted to 85 rotatably receive the swingable stanchion when the same is engaged with the side of the glass panel.

2. A convertible automobile body having a door provided with a sliding glass panel, and a swingable stanchion pivoted at one end to one side of the door and foldable down against the top of the door when the sliding glass panel is contained therein, and adapted to be positioned vertically above the 90 door at one side thereof to receive one side of the glass panel when the same is disposed above the door, and a socket aligned with the axis of swing of the door and adapted to rotatably receive the upper end 95 of the stanchion when the same is positioned vertically above the door.

3. A convertible automobile body having a door provided with a sliding glass panel, an extensible stanchion including an inner channel member engaged with one side of the glass panel, an outer channel member in which the inner channel member is fitted for limited sliding movement, the outer channel member being mounted for limited sliding movement in the door, and a swingable channel stanchion engageable with the opposite side of the panel in the raised position thereof, and foldable down over the top 100 of the panel in the lower position thereof, and a socket aligned with the axis of swing 105 of the door and adapted to rotatably receive the swingable stanchion when the same is engaged with the glass panel.

4. A convertible automobile body having a door provided with a sliding glass panel, an extensible stanchion including an inner channel member engaged with one side of a glass panel, an outer channel member in which the inner channel member is slidably 115 fitted, means for limiting the relative sliding movement of the channel members, the outer channel member being mounted for limited sliding movement in the door, said outer channel member having a lateral guide 120

rib, a door having a slot in which the lateral guide rib is slidably fitted, a swingable channel stanchion pivoted at one end to the door and foldable down against the top of the door when the sliding glass panel is contained therein, and adapted to be positioned vertically within the door at the side thereof to receive the side of the glass panel opposite

that engaged by the extensible stanchion when the glass panel is disposed above the door, and a resilient socket mounted on the body and alined with the axis of swing of the door and adapted to rotatably receiving the upper end of the swingable stanchion when the same is engaged by the glass panel.

PALEMON H. GASKINS.
